UNITED STATES PATENT OFFICE.

JESSE R. SMITH, OF BENTON, ILLINOIS.

RAILROAD-TIE RENEWER.

1,081,162.

Specification of Letters Patent.

Patented Dec. 9, 1913.

Application filed April 18, 1913. Serial No. 762,141.

To all whom it may concern:

Be it known that I, JESSE R. SMITH, a citizen of the United States, residing at Benton, in the county of Franklin and State 5 of Illinois, have invented new and useful Improvements in Railroad-Tie Renewers, of which the following is a specification.

This invention is an improved railway tie renewer especially adapted for use by section hands for removing old ties and substituting new ones in their stead, the object 10 of the invention being to provide a novel machine of this character which is adapted for use in removing or replacing ties by 15 pulling the same lengthwise from beneath the rails without the necessity of shoveling out and replacing the earth and ballast when thus replacing them and also without the necessity of marring the ties by sticking 20 picks in them to enable them to be readily handled.

This invention is an improvement on the railway tie puller for which Letters-Patent 25 of the United States, No. 924,391, were granted to me June 8, 1909, one object of the present invention being to increase the power 30 of the tie renewer so that it may be readily operated by one man when putting in or removing a tie; another object being to effect 35 improvements in the construction of the frame which carries a winch or roller, another object being to provide means for controlling the cables or chains to prevent them from tangling around in the way while the 40 machine is not in use; a further object being to effect improvements in the means for fastening the cables to the drums of the roller or winch, the invention consisting in the construction, combination and arrangement 45 of devices hereinafter described and claimed.

In the accompanying drawings:—Figure 1 is a plan of a portion of a railway track, showing one of my improved tie renewers in use thereon for removing a tie. Fig. 2 is a 50 side elevation of my tie renewers in use, the track being shown in cross section. Fig. 3 is a vertical section on the plane indicated by the line *a—a* of Fig. 1. Fig. 4 is a vertical sectional view on the plane indicated by 55 the line *b—b* of Fig. 1.

I will first describe the construction of the frame of my improved railway tie renewer. A pair of blocks 1—2 which form the sides of the frame are provided and 55 these blocks have their outer ends secured at their lower corners on a supporting bar 3

which rests on the ties on opposite sides of the tie to be pulled in or out. The length of this supporting bar is such as to enable it to bear on two ties and to span over an intermediate tie and the central portion of the supporting bar is raised as at 4 so that an arch is formed to clear the tie which is to be moved. The inner ends of the blocks 1—2 are provided with nose portions 5 which are shaped to fit against the web of one of the track rails and between the outer base flange and the head thereon. Hence, the outer ends of the blocks or side members of the frame are supported by the bar 3 while their inner ends are engaged directly with and supported by the rail at one side of the track. These blocks or side members of the frame are provided on their upper sides with handles 6 which facilitate 75 the carrying of the tie renewer from place to place and the handling thereof.

The cable controlling bar 7 is connected to the blocks or side members 1—2 of the frame at points near their inner ends and at their 80 lower sides, the said bar being provided with guide slots 8 near its ends and its central portion being arched as at 9 to clear the tie to be operated on.

An axle rod 10 connects the block or side 85 members 1—2 and passes through openings in or near the centers of said members. This axle rod is secured in place by washers 11 which bear on the outer sides of the members 1—2 and nuts 12 which are secured on 90 the ends of the axle rod, the axle rod serving as a brace to strengthen the construction of the frame and also serving as an axle for the winch 13 which is mounted revolvably thereon, the axle rod extending 95 through a central bore with which the winch is provided. The winch is here shown as having a central portion 15 near the ends and as provided at one end with a spur gear 16 which is arranged at the inner side of 100 the block or member 1 and a ratchet wheel 17 which is arranged at the inner side of the block or member 2. This ratchet wheel is engaged by a pawl 18 which is pivotally connected to the block or member 2 by means 105 of a pivot bolt 19 and the said pawl and ratchet wheel while permitting the winch to turn in the direction indicated by the arrow in Fig. 2 prevent the winch from turning in the reverse direction.

A pair of standards 20—21 are arranged 110 on opposite sides of the block 1 and extend

upwardly and inwardly from the supporting bar 3. A shaft 22 is mounted in bearing openings in the block 1 and standards 20—21 and has a squared portion on which a spur gear 2 is fitted, the spur gear being arranged on the inner side of the block 1 and engaging the gear 16. The gear 23 is of less diameter than the gear 16. A ratchet wheel 24 is also fitted on a squared portion of the shaft 22 at a point between and spaced from the block 1 and standard 21. A hand lever 25 is provided with a fork 26 at its lower end, the arms of the fork being on opposite sides of the ratchet wheel 24 and pivotally mounted on the shaft 22. A pawl 27 is pivotally mounted in the fork of the lever 25 and engages the ratchet wheel 24. A forked brace 28 is also provided which has outwardly converging members 29 and is provided at its outer end, where the members 29 converge with an opening through which one end of the shaft 22 extends so that the said shaft also has a bearing in the forked brace. The shaft is prevented from moving endwise by washers 29' and nuts 30 which are on its ends as shown. The rear or inner ends of the members 29 of the forked brace are secured to the upper and lower portions of the block 1 by means of bolts 32. This forked brace coacts with the standards 20—21 to form bearings for the shaft which carries the spur gear 23 and ratchet wheel 24 and also serves to greatly strengthen the shaft and the frame, as will be understood.

Wire cables, which constitute flexible members are secured each at one end to one of the drums of the winch the said ends of the wire cables being arranged in conical openings 34 in the drums and secured there-in by casting Babbitt metal or other suitable metal in said openings, hence, the said cables are so securely fastened to the drums that there is no danger of their breaking therefrom. These cables are adapted to be wound on the drums and unwound therefrom and are passed through the openings or slots 8 of the cable controlling bar 7 and provided at their free ends with swivels 35 to which are connected links 36, hooks 37 being connected to the said links.

Guide rollers 38 for the cables are mounted on U-shaped spring supports 39 which extend from and are carried by the cable controlling bars 7. These rollers bear against cables and prevent them from becoming kinked.

In the operation of my invention, for the purpose of removing a tie or putting a new tie in place of one which has just been removed, the frame is placed with its supporting bar bearing on ties on opposite sides of the one to be moved and with the noses or inner ends of the blocks 1—2 of the frame bearing against the outer side of one of the rails.

The cables are attached to the tie to be moved by extending the links and hooks to the cables across the end of the tie and engaging the hooks together so as to secure the cables together and to the tie and the operator imparts oscillating motion to the hand lever. Each down stroke of the lever 25 causes its pawl 27 to coact with the ratchet wheel 24 to partly turn the shaft 22 and, hence, also the spur gear 23 in the direction indicated by the arrow *a* in Fig. 2 and the said spur gear 23 by being engaged with the larger gear 26 causes the winch 14 to be partly rotated but to a less extent in the direction indicated by the arrow *b* of Fig. 2.

On each upstroke of the hand lever the ratchet wheels 17 and pawl 18 prevent retrograde rotation of the winch and, hence, as the result of continued operation of the hand lever and its connections the winch is slowly revolved by a step-by-step motion and caused to wind up the cables and, hence, draw the tie in the direction required for removing it from under the rails or placing it in position under the rails, according to the side of the track on which the device is used.

Owing to the fact that the gear 16 is of greater diameter than the gear 23 which is directly turned by the operation of the hand lever, great leverage is obtained and it is rendered easy for one man to remove or replace a tie by the employment of my improved machine.

Since the tension of the cables is on the under side of the winch, the tension of the cables is utilized in holding the nose end of the frame in place against the track rail, and since the supporting bar 4 bears on the upper sides of the fixed ties there is no possibility of the machine getting out of place while the same is in use.

I claim:

1. A tie renewer comprising a winch, a frame in which the winch is mounted, the said frame being arranged to be placed on a railroad at one side of a rail, cables connected to the winch for winding thereon, guide rollers for the cables to bear against the cables on the winch, and spring supports for the guide rollers and carried by the said frame.

2. A tie renewer comprising a winch, means for mounting the same on a railroad on one side of a rail, flexible members for winding on the winch and attachment to a tie, a gear fixed to the winch for rotation therewith, a smaller gear engaging the first-mentioned gear, a ratchet wheel connected to the smaller gear for rotation therewith, a lever and pawl carried thereby to coact with the ratchet gear to impart a step-by-step rotation to the larger and smaller gears and hence also to the winch, and means to prevent reverse rotation of the winch.

3. A tie replacer comprising a frame, a

winch mounted for rotation in the frame, means to operate the winch, cables attached to the winch for winding thereon, a cable controlling bar with which the frame is provided, said bar having guides for the cables, spring supports carried by said bar and rollers to bear against the cables and mounted in said spring supports.

4. In a railway tie renewer, a frame comprising side members and a supporting bar connected to the side members at one end, a winch arranged between the side members and carried thereby, cables attached to the winch, a gear at one end of the winch and revoluble therewith, an operating shaft, bearings therefor with which the frame is provided, a small gear and a ratchet wheel carried by the operating shaft, said small gear being engaged with the gear of the 20 winch, a lever mounted for pivotal movement on the operating shaft, a pawl carried by said lever and for engagement with the ratchet wheel, and means to prevent reverse rotation of the winch.

5. In a tie renewer, a frame comprising a supporting bar, side members arranged on one side of and extending from the support-

ing bar, a cable controlling bar connecting said side members and spaced from the supporting bar, a winch mounted between the side members, a gear mounted for rotation with the winch and at one end thereof, standards carried by the supporting bar and arranged at opposite sides of one of the side members, an operating shaft mounted in said standards and also in said last-mentioned side member, a small gear and a ratchet wheel on said operating shaft for rotation therewith, the small gear engaging the gear of the winch, a lever having a fork pivotally mounted on the operating shaft and astride of the ratchet wheel, a pawl carried by said lever to engage the ratchet wheel, a forked brace connected to the last named side member and also having a bearing for the operating shaft, and means to prevent reverse rotation of the winch.

In testimony whereof I affix my signature in presence of two witnesses.

JESSE R. SMITH.
